CENTRIFUGAL BOWL WITH RECIPROCATING VALVE FOR SEPARATING SLUDGE-CONTAINING LIQUIDS

Tore Verner Hanno, Stora Essingen, Sweden, assignor to The De Laval Separator Company, New York, N. Y., a corporation of New Jersey

Application May 20, 1944, Serial No. 536,462
In Sweden July 13, 1943

5 Claims. (Cl. 233—20)

1

When separating sludgy liquids in a centrifugal bowl of ordinary construction, the bowl is filled with sludge after a relatively short time and must then be stopped for cleaning. For separating problems of this kind it is therefore preferred to use centrifugal bowls provided either with small nozzles in the wall of the bowl and designed for continuous discharge of the sludge, or with devices for intermittent discharge of the sludge during operation. In the latter case a construction of centrifugal bowl is generally used which permits the upper or the lower part to be moved axially relative to the other parts of the bowl, a slot thereby being formed thru which the contents of the bowl escape. Such a construction, however, has the convenience that a dry sludge cannot be discharged, because the liquid contained in the bowl flows out together with the sludge, and this entails the further inconvenience that the supply of liquid to the bowl must be shut off each time the bowl is to be emptied.

With a view to avoiding these inconveniences a plurality of devices comprising openings or channels in the bowl wall have been suggested. In these constructions the openings are covered either by an axially movable slide or by valves, susceptible of being opened during operation. The inconveniences with the known devices comprising a slide are the difficulty to obtain large packing rings of sufficient durability and capable of making a tight joint, and above all to get the opening intervals sufficiently short, so that only part of the sludge contained in the bowl is discharged each time. The valves heretofore suggested are complicated and sensitive and often untight, because sludge particles easily penetrate between the cone and the seat of the valve.

The object of the invention is an arrangement in centrifugal bowls, the wall of which is provided with channels or openings for the discharge of the sludge separated in the bowl, which channels or openings are covered by one or more movable members, for instance slides or the like, provided with openings which, when the movable members occupy a given position, communicate with corresponding openings in the bowl wall, and is characterized in that each outlet opening in the bowl wall is provided with a tightening device, e. g. in the form of an elastic pack-

2

ing, collar, etc., making a tight joint both with the bowl wall and the slide. In a preferred construction the packing is thereby fixed to the bowl wall by means of an annular nut or the like. The pressure establishing the tight joint with the slide is generated both by the centrifugal force and the liquid pressure. In order to enable quick opening and closing each outlet opening should advantageously be provided with a small slide.

10 Figure 1 of the accompanying drawing shows one embodiment of the invention in longitudinal section. Figure 2 is a cross section on the line 2—2 of Figure 1. Figures 3, 4 and 5 are views in longitudinal section of other embodiments of the invention.

15 In all figures the following denominations are used: 1 is the lower part or shell of the centrifugal bowl, carried by a bowl spindle 2. 3 is the upper part or top of the bowl, and 4 its annular outlet for separated liquid; 5 a coupling ring by which the bowl top 3 and the bowl shell 1 are held together. 6 is a receiver and distributor of unseparated liquid, and 7 is the supply pipe for the liquid. 38 is a pile of conical discs. On its 20 largest inner diameter the bowl shell 1 is provided with a number of round openings 8, each of which opens into a cylindrical chamber 9, positioned at right angles to the openings and communicating with the outside of the bowl thru the oblong opening 10. The cylindrical chamber 9 is provided with an exchangeable lining 11 and its upper end is covered by a screw-plug 12; in the chamber 9 there is a cylindrical slide 13, provided on the middle with a plane surface 14. An opening 15 is provided at right angles to the surface 14.

25 In each of the openings 8, which are provided with a threaded part 16, is arranged a sleeve- or cup-shaped packing 17 having a central opening 18 and a flange 19, the latter being squeezed fast to the bowl shell 1 by the annular nut 20 and the outer part of which contacts with the plane surface 14 on the slide 13. The length of the slide 13 is less than that of the cylindrical chamber 9.

30 On the lower side of the centrifugal bowl two receiving chambers 21 and 22 are arranged into which a servo liquid can be fed thru the stationary tubes 23 and 24. The chamber 21 communicates with the lowermost part of the cham-

ber 9 by a channel 25 and the chamber 22 with the uppermost part of the same chamber thru a channel 26.

In the embodiment according to Fig. 1, the bowl shell 1 is provided with a drain channel 27 running from the upper part of the chamber 9 to the outside of the bowl and located at a distance from the lower side of the screw plug 12 approximately equal to the difference between the length of the chamber 9 and that of the slide 13, that is the length of stroke of the slide. Another channel 28 is provided at the same distance from the bottom of the chamber 9. The opening 15 in the slide is so located as to communicate with the opening 18 in the packing 17 when the slide occupies its highest position.

The bowl operates in the following manner.

Servo liquid is fed thru tube 24 into the chamber 22 whence it passes thru the channel 26 to the upper end of the slide which is thereby forced down to its lower position, so that the communication between the openings 15 of the slide and the opening 18 of the packing is interrupted. The supply of servo liquid is now shut off, and the liquid contained in the chamber 22, the channel 26, and the upper part of the chamber 9 escapes thru the opening 27, since this is not covered. When a suitable amount of sludge has accumulated in the sludge space of the bowl, servo liquid is introduced into the chamber 21 and is conducted thru the channel 25 to the lower end of the slide, which is then forced up until the openings 15 and 18 communicate, whereupon the supply of servo liquid is shut off. When a suitable amount of sludge has been thrown out, the opening in the bowl is closed again by feeding liquid into the chamber 22. It is thus necessary to use servo liquid only at the opening and closing intervals, and consequently the consumption of such liquid is very small.

If the opening interval must be very short in order to prevent liquid from escaping with the sludge, the construction of slide shown in Fig. 3 may be used. The opening 15 of the slide is placed in such a manner that the communication between the openings 15 and 18 is interrupted both in the uppermost and the lowermost position of the slide, that is the openings communicate with each other only when the opening 15 is passing the opening 18. By regulating the supply of servo liquid it is possible to change the speed of the slide and thus to shorten the opening interval down to a fraction of a second. In that case only one of the tubes 23 and 24 need be used for a complete emptying operation.

In order to make a satisfactory tight joint the packing 17 should be made of an elastic and comparatively soft material, but this entails rapid wear of the packing in case hard sludge particles penetrate between the packing and the slide. With a view to preventing this, the packing 17 in Fig. 3 is provided with a sleeve 29 of metal, Bakelite, or another hard and resistive material. The sleeve should have sharp edges, especially on its inside, on the part contacting with the slide, because sludge particles are then prevented from getting between the slide and the packing. In order to avoid deformation of the cylindrical part of the packing sleeve by the high interior pressure, a reinforcing sleeve of metal or the like may be arranged around this part, or the opening 8 may be so dimensioned, as shown in Fig. 3, that there is only a small play between the packing sleeve and the wall of the bowl shell.

Although only two embodiments are illustrated, 75

it will be understood that a great many modifications are possible within the scope of the invention. The packing sleeve 17 need not have any special shape or be of any special material. It may, for instance, be in the form of metal bellows 30 (see Fig. 4) to which packing material is vulcanized. Instead of supplying servo liquid at both ends of the slide, a spring 31 (see Fig. 5) may be arranged at its one end by which the slide is forced back into its initial position. In this case a drainage must however also be provided, for instance in the form of a small opening 32 thru which the servo liquid escapes from the chamber 9.

What I claim and desire to protect by Letters Patent is:

1. In a centrifugal bowl the wall of which encloses a number of chambers extending parallel to the axis of the bowl, the bowl wall having discharge openings one between each chamber and the outside of the bowl, the bowl wall having inner openings one between each chamber and the inside of the bowl, sliding members, one in each chamber, each having a longitudinally extending plane inside surface and a through orifice adapted, in one position of the sliding member, to connect the two openings, means, including a channel through which a servo liquid is adapted to flow, whereby the movement of each sliding member is controlled, and in each inner opening a packing device having an opening communicating with the corresponding inner bowl wall opening and making a tight joint both with the bowl wall and with the plane surface of the sliding member.

2. A centrifugal bowl comprising a wall having an outlet opening communicating with the interior of the bowl, a packing device mounted in the opening and defining a passage for the discharge of solid particles and sludge separated in the bowl, the packing device making a tight joint with said wall to seal the opening except for said passage, a reciprocable member slidable in the bowl wall and having a surface maintaining a tight joint with the packing device around said passage in the movement of the member, said member being operable in its movement to alternately open and close said passage, and means for controlling the movement of the sliding member.

3. A centrifugal bowl as defined in claim 2 in which the packing device includes a flexible element having a wear-resistant sleeve defining said passage and contacting said surface of the slideable member.

4. In a centrifugal bowl the wall of which is provided with a plurality of separate openings communicating with the interior of the bowl for the discharge of solid particles and sludge separated in the bowl, sliding members, one covering each opening, each sliding member being provided with an outlet, means, including a channel in which a servo liquid is adapted to flow, by which the movement of said member is controlled, and a packing device in said opening; said packing device comprising an elastic cup-shaped member having a part contacting the sliding member and having an opening in said contacting part communicating with the corresponding inner bowl opening and having, around the other end, an exterior flange, and an annular nut securing the said flange to the bowl wall, thereby making a tight joint with the bowl wall and with the plane surface of the sliding member.

5. In a centrifugal bowl the wall of which is

provided with a plurality of separate openings communicating with the interior of the bowl for the discharge of solid particles and sludge separated in the bowl, sliding members, one covering each opening, each sliding member being provided with an outlet, means, including a channel in which a servo liquid is adapted to flow, by which the movement of said member is controlled, and a packing device in said opening; said packing device comprising a cup-shaped flexible member having a part contacting the sliding member and having itself an opening in said contacting part communicating with the corresponding opening communicating with the interior of the bowl, and a wear-resistant sleeve surrounding the opening adjacent the sliding member and in contact therewith.
